UNITED STATES PATENT OFFICE

130,954

DESIGN FOR A FERN STAND OR THE LIKE

Ernst Pirnstill, Cleveland, Ohio

Application June 18, 1941, Serial No. 101,521

Term of patent 7 years

To all whom it may concern:

Be it known that I, Ernst Pirnstill, a citizen of the United States, residing at Cleveland, in the county of Cuyahoga and State of Ohio, have invented a new, original, and ornamental Design for a Fern Stand or the like, of which the following is a specification, reference being had to the accompanying drawing, forming part thereof, wherein Fig. 1 is a side elevational view of a fern stand, showing my new design; Fig. 2 is a perspective view thereof, the bulbs illustrated in dotted lines in Figs. 1 and 3 being omitted; and Fig. 3 is a top plan view. The characteristic features of the design are shown in full lines.

I claim:

The ornamental design for a fern stand or the like, as shown and described.

ERNST PIRNSTILL.
